ROBERT WILHELM VOIGT, OF DRESDEN, GERMANY, ASSIGNOR TO THE FIRM "UNIVERSSELLE" CIGARETTEN-MASCHINEN-FABRIK J. C. MÜLLER & CO., OF DRESDEN, GERMANY

DEVICE FOR FORMING GROUPS OF A DEFINITE NUMBER OF ARTICLES

Application filed May 21, 1929, Serial No. 364,834, and in Germany May 25, 1928.

In the mechanical packeting of rod-shaped or like goods, in particular, cigarettes, it is necessary to form the cigarettes or the like into a group of a definite number and to introduce this group into the packet or box. The cigarettes or the like must be fed to a collecting station and after the number necessary to form the group has been collected the group must be transferred from the collecting station to the packeting station or the like, this transfer being usually effected by means of plungers or the like. The formation of the groups occupies a certain amount of time as also does the transfer of the group into the packet or box so that there is a definite working rhythm which requires that the number necessary to form a group must be combined with certainty in a working phase. There is however some uncertainty as the means for feeding the cigarettes or the like to the collecting station for the groups occasionally leaves gaps and the group is not completely formed within the time available and consequently too few cigarettes are pushed into the packet—a disadvantage which must be avoided at all costs.

As the formation of gaps in the feeding means cannot be avoided or can only be avoided with difficulty the present invention consists in delivering to the collecting station in a working phase a number of articles in excess of the number to form the group, a counter or the like interposed in the feed track being adapted to be actuated by the arriving articles and after counting off the number to form a group so operating a valve or the like that any further articles fed towards the conclusion of the working stroke are led off from the feed track.

Preferably the articles (cigarettes) are fed separately in pockets or recesses in a continuously moving endless band to a bridge disposed in front of a collecting channel over which they are pushed by a feeding means, for example a rotating cross or the like, to the collecting channel, the cigarettes lying in the pockets entering the interdental spaces in a toothed counting wheel which is provided with a number of teeth in excess of the number of the group and which after a rota-

tion corresponding to the number of a group operates an electromagnet in such manner that the bridge controlled by this electromagnet is released to the action of a spring or the like which so moves the bridge that the succeeding articles are led out of the feed track to the collecting channel while after the conclusion of the complete rotation of the counting wheel the original condition is restored.

The new apparatus is illustrated in the accompanying drawing in Fig. 1 in side elevation and in Fig. 2 in vertical cross section on the line 2—2 of Fig. 1.

Referring to the drawing, the separate cigarettes Z are fed by suitable means (not shown in the drawing) separately into pockets or recesses 1 on an endless band 2 or an endless chain which moves continuously with uniform speed over the pulley 3 in the direction of the arrow. The parallelly disposed pockets 1 are arranged at regular distances apart on the band 2. The cigarettes are delivered to the pockets on the upper flight of the endless band and fed to a bridge 4 the free end of which engages in known manner by means of projecting tines the cigarettes resting in the pockets 1. The cigarettes passing in this manner to the bridge are pushed by the blades 5 of a blade wheel 6 rotating in the direction of the arrow over the bridge to the collecting channel 7 which is provided with an abutment or stop 8 and in which can be collected a group of cigarettes of pre-determined number (a group of nine in the embodiment shown). The bridge 4 is pivotally mounted at 9, the downwardly extending projection 10 constituting the armature of an electromagnet 11. The electromagnet excited by electric current holds the bridge 4 in the position shown in full lines in Fig. 1 against the action of a spring 12 connected at one end to the armature 10 and at its other end to a pin 13.

The contact for the circuit of the electromagnet is formed by two stationary discs 14 and 15 to which the conductors 16 and 17 are connected. Between the discs extend a contact carrier 18 the axially disposed pin 19 of which contacts with the two contact discs, 100

the pin being insulated. The contact carriers are mounted on the hub 19 of a toothed wheel 20 which hub extends through a central aperture in the disc 14 and is mounted to rotate freely on spindle 21.

5 As is clear from Fig. 1, the teeth 22 enter the spaces between two adjacent cigarettes in the pockets 1 at the point where the cigarettes 2 extend with their ends beyond the 10 pockets 1 (see Fig. 2). The cigarettes thus turn the freely rotatable pinion 20 on the spindle 21. The number of teeth of this pinion is such that after a complete revolution of the pinion more cigarettes are supplied than are required to form the group in the 15 channel 7. In the embodiment illustrated, the group consists of nine cigarettes while the pinion has ten interdental spaces. Adjacent the last or excess space the contact 20 disc 15 is provided with a recess 23 so that the contact pin 19 cannot close the circuit when it moves into the space 23. The circuit is accordingly interrupted so that the electromagnet 11 releases its armature 10 and 25 the bridge 4 under the action of the spring 12 swings on its pivot, i. e. moves into the position shown in dotted lines in Fig. 1. With the bridge in this position the cigarettes now arriving cannot pass to the bridge 30 (which naturally is provided with slits for the passage of the blades 5) so that the supply to the channel 7 is interrupted.

It should be observed that within one working phase the feed band 2 is moved forward 35 through a definite amount in such manner that more cigarettes are supplied than are necessary to form a group. Moreover the cigarettes supplied are counted by the counting wheel 20 and the further supply to the 40 channel stopped immediately when the number of cigarettes necessary to form the group has been fed. The excess supplied by the band 2 ensures that this number is always maintained so that it does not matter should 45 one of the pockets not contain a cigarette since the counting wheel 20 is arranged to provide an excess and is only rotated when actually a cigarette disposed in a pocket imparts a movement thereto. Naturally the 50 excess can be increased if desired so that instead of supplying ten cigarettes in one working phase as in the embodiment illustrated, twelve or fourteen cigarettes can be supplied. In general, however, the safety factor referred to is sufficient as it seldom happens 55 that the pockets are not fed with cigarettes.

I claim:

1. A device for forming groups of a definite number of articles with uninterrupted supply of the articles along a feed track, comprising a collecting station, means for feeding a number of articles exceeding the number required to form the group to the collecting station, a counting mechanism disposed in front of the collecting station and

operated by the articles and a valve operable by the counting mechanism to allow surplus articles to move out of the feed track.

2. A device for forming groups of a definite number of articles with uninterrupted supply of the articles along a feed track, comprising a collecting station, means for feeding a number of articles exceeding the number required to form the group to the collecting station said feeding means including an endless band, said band formed with pockets for the articles, a bridge member disposed in front of the collecting station, feed means for feeding the articles over the bridge a counting wheel disposed in front of said feed means said wheel having teeth exceeding in number the number of articles to form a group, the teeth being adapted to receive the articles from the pockets of the endless band, and an electric circuit controlled by said counting wheel in such manner as to cause the bridge member to rock to lead excess articles from the feed track.

In testimony whereof I affix my signature.

ROBERT WILHELM VOIGT.
